UNITED STATES PATENT OFFICE

MYRON L. BEGEMAN AND PAUL F. GUTMANN, OF ST. LOUIS, MISSOURI, ASSIGNORS TO
MISSISSIPPI GLASS COMPANY, OF NEW YORK, N. Y., A CORPORATION OF NEW YORK

APRON CONTROL OF GLASS MACHINES

Application filed May 21, 1929. Serial No. 364,753.

In the manufacture of sheet glass by the continuous process, the newly formed plastic sheet, after leaving the forming rolls, passes over an apron en route to the leir. 5 After being formed the sheet rests on the lower roll for a certain predetermined arc of rotation and then encounters the nose of the apron, which guides the sheet onto the apron.

In order to properly control the cooling 10 and chilling of the new sheet, it is advisable to be able to regulate the duration of contact of sheet and roll, and in order to do this the apron is adjustable as to position.

The object of this invention is to provide 15 devices whereby the position of the apron nose may be adjusted by a single simple operation, and without changing the distance or gap between roll and apron nose.

Further and other objects and advantages 20 will be apparent from the specifications and claims, and from the drawings which show by illustration what is considered the preferred embodiment of the invention.

Fig. 1 is a side elevation of one modification of the invention.

Fig. 2 is a side elevation of another modification of the invention in which not only the nose of the apron, but the entire surface of the apron adjacent the roll, is kept at a 30 fixed distance from the roll in all positions of adjustment.

Fig. 3 is a section on the line 3—3 of Fig. 2 showing details of the adjusting device.

Referring to Fig. 1, molten metal flows 35 from the right between upper and lower rolls 10 and 12, to emerge as sheet 14. The sheet rests on roller 12 until it encounters nose 16 of the apron 18, whereupon the sheet passes over the top of the apron en route to the leir. 40 The apron is built in sections rigidly mounted on bar 20 which is provided at its lower end with rollers 22 resting on a plate 24. The upper end of the apron is provided with brackets 26 through which passes a trunnion 45 rod 28, extending from side to side of the apron. Rod 28 passes through a curved slot 30 in a vertical plate 32 rigidly mounted at each side of the apron. Plates 32 may be held at the desired height by means of bolts 50 34 passing through selected holes 36 in the

plate. The plates may be moved longitudinally by screws 38 as indicated in the drawings, so as to fix the width of the gap between apron nose 16 and roller 12. When the desired gap is obtained plates 32 are locked in 55 position by screws 40.

Engaging the ends of rod 28 are the eyes 42 of adjusting screws 44. Each screw is provided with a flanged self-aligning nut 46 supported for rotation in a socket 48 provided with a trunnion 50 free to rotate in a bracket 52 fast on the frame. The flange of nut 46 is drilled to provide sockets 54 to accommodate a bar or wrench.

It will be evident that when nuts 46 are 65 turned the upper end of the apron will be raised or lowered through the instrumentality of screws 44. As the apron is moved vertically, slots 30, by their engagement with rod 28, constrain the apron to so move as to 70 preserve unchanged the gap between nose 16 and roll 12.

The swiveled sleeves 48 permit screws 44 to follow slot 30, and rollers 22 on plate 24 permit the free end of the apron to move 75 back or forth when the other end of the apron is adjusted.

Fig. 2 shows a modified form of the invention in which the apron instead of being rigid is jointed, and two adjusting slots are provided for a purpose which will appear.

The upper apron section 60 is hinged at its lower corner on rod 28 by means of brackets 62, and plates 32 are replaced by plates 64 having lower and upper arcuate slots 66 85 and 68 respectively, struck on radii from the center of the lower roll 12. Rod 28 engages lower slot 66 and studs 70 set into the sides of apron section 60 near the nose thereof engage upper slots 68. With the above in mind it will be apparent that the adjustment of nuts 46 will cause rod 28 and studs 70 to follow arcuate paths about the center of the lower drum, thereby maintaining all parts of section 60 at constant distances from the 90 drum.

The two lower apron sections are rigidly mounted on bars 72 which at their lower bent ends are free to slide on the machine frame. The upper ends of bars 72 are hinged on rod 100

28 by means of brackets 74. Except at the lowest position of the apron there is a gap between the low end of upper section 60 and the high end of the second section. If this 5 gap becomes extreme, an air cooled pipe 76 is placed as shown in Fig. 2 to help carry the sheet over the gap.

It is to be understood that the invention is not limited to the specific embodiment and 10 construction herein described but may be used in other ways without departure from its spirit as defined by the following claims.

We claim—

1. In apparatus for making sheet glass, in 15 combination, upper and lower rolls adapted to form a glass sheet, an apron having a nose adjacent said lower roll and adapted to conduct the sheet away from said roll, and means for adjusting the nose of said apron vertically while maintaining said nose at a constant distance from said roll, said adjusting means comprising a member fixed on said apron and devices constraining said member to follow a fixed path.

25 2. In apparatus for making sheet glass, in combination, upper and lower rolls adapted to form a glass sheet, an apron having a nose adjacent said lower roll and adapted to conduct the sheet away from said roll, and means 30 for adjusting the nose of said apron vertically while maintaining said nose at a constant distance from said roll, said adjusting means comprising a fixed guide member which constrains the apron to move in a pre- 35 determined path.

3. In apparatus for forming sheet glass, in combination, an upper roll, a lower roll, an apron having a nose adjacent said lower roll, a self-aligning nut, a screw threaded through 40 said nut and adapted to adjust said apron vertically when said nut is turned; and guiding devices operative when said apron is adjusted for maintaining the distance between said apron nose and said lower roll.

45 4. In apparatus for forming sheet glass, in combination, an upper roll, a lower roll, an apron having an end adjacent said lower roll, a self-aligning nut, a screw threaded through said nut and adapted to adjust said apron vertically when said nut is turned; and guiding devices operative when said apron is adjusted for maintaining the distance between the end of said apron and said lower roll.

5. In apparatus for forming sheet glass, in 55 combination, an upper roll, a lower roll, an apron having an upper section adjacent said lower roll, and means operable to adjust said upper section circumferentially about said lower roll, said adjusting means comprising a plurality of guiding devices operable on 60 said section, substantially as described.

6. In apparatus for forming sheet glass, in 65 combination, an upper roll, a lower roll, an apron having an upper section adjacent said lower roll, and means operable to adjust said

upper section circumferentially about said lower roll, said adjusting means comprising a plurality of fixed guiding devices and manually operable means for forcing said section to follow said guiding devices.

7. In apparatus for making sheet glass, in combination, a roll, an apron, means for adjusting one end of said apron circumferentially of said roll, and means supporting the other end of the apron for horizontal motion 75 when said adjustment is made.

8. In apparatus for making sheet glass, in combination, a roll, an apron having an upper section, means for adjusting said upper section circumferentially of said roll, a horizontal guide, and a hinge between said upper section and the lower portion of said apron whereby said lower portion may constantly rest on said guide in any position of adjustment of said upper section.

In testimony whereof we hereto affix our signatures.

MYRON L. BEGEMAN.
PAUL F. GUTMANN.
